[57] CLAIM

The ornamental design for automatic feeder for pets,
substantially as shown.

DESCRIPTION

FIG. 1 is an exploded perspective view taken from the
top, one side and one end of an automatic feeder for pets
showing our new design;

FIG. 2 is an elevational view taken from the side oppo-
site that shown in FIG. 1;

FIG. 3 is a top plan view thereof; and

FIG. 4 is a bottom plan view thereof.
